UNITED STATES PATENT OFFICE.

JOHN BERGESEN, SR., OF BROOKLYN, NEW YORK.

DERRICK.

Application filed August 26, 1927. Serial No. 215,639.

This invention relates to derricks of a type adapted particularly for securing in a window opening of a building and operable from within the same whereby to hoist material through such opening, the invention having for an essential object the construction of a substantial, portable, and adjustable support for the derrick for securing the same within the window opening and which may be easily moved, transported, and re-erected in different windows of the building.

A further object is to provide a boom for the derrick which is normally arranged in a substantially horizontal position whereby to extend outwardly from the mast thereof and adapted to be automatically moved into an upper or substantially vertical position as the load carried by the boom reaches or approaches the window opening so as to permit the boom and the load to be swung inwardly to within the building.

A further object comprises the arrangement of supporting rods, braces and clamps for securely retaining the derrick in position within the window opening, and including a support extending within the building adapted for attaching a platform mounting a hoisting winch for operating the cable carried by the boom, said winch being provided with a combined clutch and brake mechanism arranged upon the opposite movement thereof to engage the drum of the winch for hoisting the cable attached thereto, or for releasing the clutch and applying the brake when the cable is desired to be lowered.

A still further object is to provide an apparatus of this character of simple and practical construction, strong and durable, efficient in performance, adapted to be easily and securely attached in operative position and otherwise well adapted for the purposes for which the same is intended.

Other objects and advantages reside in the special construction and combination of the various elements forming the invention, reference being had to the accompany-

ing drawings forming a part hereof, where-

in:

Figure 1 is a vertical sectional view 50 through a window opening showing the apparatus in elevation secured in position for operation therein.

Figure 2 is an elevational view thereof 55 taken from the outside of the window within which the derrick is attached.

Figure 3 is an end elevational view of the hoisting winch.

Figure 4 is a top plan view thereof.

Figure 5 is a detail in side elevation of 60 the combined clutch and brake mechanism for the winch.

Figures 6 and 7 are plan views of the cable guide mounted on the boom.

Figure 8 is a vertical sectional view 65 through the combined cable hoisting and boom elevating pulley.

Figure 9 is a view in elevation of one section of the pulley wheel, and,

Figure 10 is a similar view of the sections of the pulley in assembled position and showing the manner of attaching the boom hoisting cable thereto.

Referring now to the drawings in detail 75 wherein for the purpose of illustration I have disclosed a preferred embodiment of my invention, I provide a derrick comprising a mast 5, preferably constructed of a pair of telescopic sections, each of said sections having openings 6 extending transversely therethrough for receiving a pin 7 whereby to secure the sections in adjusted extended position. The lower end of the mast 5 is seated within one section of a 80 tubular T-joint 8, invertedly arranged with its horizontal section 9 slidably carried on a horizontally disposed rod 10, the horizontal section of said joint and the rod also having openings 11 formed transversely therein for 85 receiving a pin 12 whereby to secure the joint in longitudinally adjusted position with respect to said rod. The rod 10 extends through a window or other suitable opening indicated generally at 13 and disposed above the sill 14 thereof, the inner and

outer ends of the rod carry clamping members 15, slidably carried on the rod 10 and secured in adjusted position thereon by set screws 16, said clamping members having 5 serrated faces 17 for engaging the inner and outer faces of the building wall 18 immediately below the window sill. Suitable wood liners 19 are interposed between the serrated faces of the clamping members and 10 the face of the wall to prevent injury thereto through the gripping engagement.

The upper end of the mast 5 likewise carries a tubular T-joint 19 having its horizontal section 20 slidably carried on an upper 15 horizontal rod 21 extending through the opposite sides of the window opening, said rod and said joint being likewise provided with transverse opening for receiving a pin whereby to secure said parts in adjusted 20 position.

The upper joint 19 is also provided with a tubular lateral extension 22 extending at right angles to the horizontal section 20 thereof and adapted to receive one end of a 25 sectional telescoping horizontally disposed rod 23 extending crosswise at the upper end of the window opening and having its opposite end provided with a pair of clamping members 24, similar in construction to the 30 clamping members 15 heretofore described and arranged for gripping relation with the opposite side of the building wall. The joints 19 also carry a pair of such clamping members 25 also arranged in gripping relation 35 with the opposite faces of the building wall, it thus being noted that the mast 5 is firmly retained in position at its upper end by a set of such clamps engaging the building wall at each side of the window 40 opening and at its lower end by a similar set of clamps. The sections of the horizontal crosswise extending rod 23 at the upper end of the window are provided with transversely extending openings 26 for receiving 45 pins 27 whereby to secure the sections of the rod in adjusted position and permitting the use of the apparatus in window openings of varying widths.

The sections of the horizontal rod 23 may 50 be threadedly engaged and adapted for longitudinal adjustment with each other by means of a force nut 23' carried on one section whereby to enable such section to be threaded into or out of said other section.

55 A boom supporting collar 28 is slidably carried on the mast 5, being supported on the upper edge of the joint 8. The collar has a series of transverse openings registering with the openings 6 of the mast for receiving 60 a supporting pin 7' whereby to secure the collar in adjusted vertical position. An offset 29 is formed on the collar through which extends a vertically disposed bore adapted to rotatably carry a pin 30 therein, 65 the upper end of the pin being formed into

a bracket 31 having transverse openings for receiving a pin 32 upon which is pivotally supported a boom 33.

A boom is formed of telescoping sections having transverse openings 34 for receiving pins 35 whereby to secure the sections in adjusted extended position, the outer end of the boom having a pulley wheel housing 36 formed thereon. As shown in Figure 8 of the drawing, the housing 36 may be formed 75 separately from the boom 33 and threadedly secured in position thereon. The outer end of the housing is provided with a guy rope attaching tip 36' which may be used for swinging the boom. 80

A shaft 37 is arranged transversely in the housing upon which is rotatably carried a longitudinally slit pulley wheel 38 having the sections thereof secured to each other by bolts or the like 39. The abutting faces of 85 the sections forming the pulley wheel have spaced parallel flanges 40 formed thereon providing a channel 41 therebetween at the center of the pulley wheel and within which is disposed a ring 42 adapted to rotate independently of the wheel by means of ball bearings 43 interposed between the ring and the base of the channel formed in the pulley wheel. The opposite sides of the housing 36 are open through which may be extended a 90 hoisting cable 44 having a section of chain 45 attached to one end thereof on which is carried a grappling hook 46. 95

The outer periphery of the ring 42 is 100 formed into a circumferential groove constituting a seat for receiving the cable 44 over which the cable is adapted to travel during the hoisting operation without interfering with the movement of the pulley wheel 38 or tending to cause the movement 105 of such pulley during the operation of the cable.

Shoulders 47 are formed upon the adjacent faces of the flanges 40 outwardly from the ring 42, the shoulders of each flange being 110 arranged opposite each other and adapted to be engaged by the edges of the horizontal links of the chains 45 as the same is drawn over the pulley by the cable 44. As soon as the links of the chain engage the shoulders 115 on said flanges of the pulley, the pulley also will be rotated as the hoisting of the cable continues.

The sides of the sections of the pulley 38 are extended to form a drum 48 to which is 120 attached one end of a boom elevating cable 49, the opposite end of which is attached to a hook 50 carried on a collar 51 secured adjacent the upper end of the mast 5. Thus it will be apparent that as the load attached 125 to the hook 46 approaches the boom so that the chain 45 will rotate the pulley in a manner heretofore explained, the pulley thereupon will wind the cable 49 about itself so as to raise the outer end of the boom up- 130

wardly and permit the same together with the load to be swung through the window opening to the interior of the building.

The cable 44 is extended through guides 52 formed on collars 53 and 54 attached to the boom, said collar 54 having ears 55 formed thereon and having openings through which bolts may be inserted for attaching the collar at the pivoted end of the boom. A pulley wheel 56 is carried by the collar 54 about which the cable 44 extends in a direction toward the interior of the building where the same is adapted to be wound about a drum 57 rotatably mounted on a winch frame 58 secured to the inner end of the rod 10. The drum may be operated in the usual manner by a worm wheel 59 engaged by a worm 60 carried on a shaft 61 to which is attached a crank 62.

20 A combined clutch and brake mechanism is interposed in the drive shaft 61, the shaft being sectionally constructed and having its adjacent ends provided with suitable clutch members 63 adapted to be moved into or out 25 of engagement with each other whereby to transmit the power from one section of the shaft to the other, one of the clutch members being provided with a throw out collar 64 rotatably carried in a groove formed 30 therein and having studs 65 extending laterally therefrom at opposite sides and engaged in slotted openings formed in one end of a bell crank 66 having its opposite ends pivoted at 67 to a shaft extending through the 35 winch frame and on the opposite ends of which are attached control levers 68 whereby to permit the operation of the bellcrank from either side of the winch.

The section of the shaft 61 connected directly with the drum has the clutch member carried thereon formed into a brake drum 69 about which is arranged a brake band 70 and operatively connected at 71 to the bell crank whereby to cause the brake band to 45 tightly engage the brake drum upon the movement of the bellcrank in a direction to disengage the clutch member.

The winch frame 58 is formed into sections including a base section 72 which is 50 fixedly attached to the rods 10 upon which the winch frame proper 58 is mounted and pivotally attached thereto by a bolt 73 at one end permitting the horizontal swinging movement of the opposite end thereof whereby to enable the angular adjustment of the 55 winch with respect to the rod 10 and the hoisting mechanism. The winch frame 58 may be secured at its swinging end to the base in adjusted position by means of bolts 60 74, the shank of which slides in a channel 74' formed in the adjacent end of the base section and defining the limitations of the movement of the bolt and thus prevent the swinging of the winch frame beyond a cer-

tain predetermined distance, as indicated by 65 the dotted lines in Figure 4.

The head of the bolt 73 is formed into a unit having a concaved upper surface as indicated at 75 in Figs. 3 and 4 for the purpose of receiving the lower end of a shoring member which extends upwardly for bracing against the ceiling of the room so as to eliminate vibrations at the winch end of the frame during the hoisting of heavy loads.

It is believed the manner of operation of 75 the apparatus will be thoroughly understood from the foregoing description without necessitating a detailed explanation of the co-action between the various parts.

It is obvious that the invention is susceptible to various changes and modifications without departing from the spirit or scope of the invention as hereinafter claimed, and I accordingly claim all such forms of the device to which I am entitled. 85

I claim:—

1. A derrick comprising a boom supporting mast, a boom mounted thereon for vertical swinging movement, a pulley arranged at the outer end of the boom and including a drum 90 and a ring mounted for independent rotation, said ring having a circumferential groove formed therein, a hoisting cable adapted to seat within said groove, operable remote therefrom, a cable attachable to the 95 mast and adapted to be wound about said drum and means carried at the end of said first named cable and engageable with the drum whereby to operate the same so as to cause the vertical movement of said boom. 100

2. A derrick comprising a boom supporting mast, a boom mounted thereon for vertical swinging movement, a pulley arranged at the outer end of the boom and including a drum and a ring arranged for independent 105 rotation, said ring having a circumferential groove formed thereabout, a hoisting cable adapted to seat within said groove, operating means for the cable, a chain attached to the end of the cable, flanges formed on said drum 110 in spaced relation and providing a channel therebetween, shoulders formed on the opposed faces of said flanges and adapted to be engaged by the links of the chain whereby to cause the rotation of the drum and a boom 115 elevating cable having one end attached to the mast with its opposite end arranged to be wound about said drum.

3. An apparatus of the class described comprising a boom supporting mast having a 120 boom mounted thereon for vertical and horizontal swinging movement, said mast and boom having a load hoisting cable operatively associated therewith, and a boom hoisting cable operatively connecting the 125 boom and the mast and normally inactive during the initial hoisting action of the first named cable and adapted during a predeter-

mined period of the movement of the first named cable to operate said boom hoisting cable.

4. A derrick comprising a boom support-
5 ing mast, a boom pivotally mounted thereon for vertically swinging movement, a cable winding drum arranged at the outer end of the boom having a boom hoisting cable operatively associated therewith, a multi-sec-

tional load hoisting cable operatively ar-¹⁰
ranged thereon said load hoisting cable hav-
ing one of its sections adapted to ride freely
over the drum and its other section adapted
for operatively engaging said drum.

In testimony whereof I affix my signa-¹⁵
ture.

JOHN BERGESEN, Sr.
